WHIP STOCK REMOVING DEVICE

Gottdank L. Kothny, Strafford, Pa., assignor to
Sperry-Sun Well Surveying Company, Phila-
delphia, Pa., a corporation of Delaware

Application September 28, 1937, Serial No. 166,064

9 Claims. (Cl. 255—1)

This invention relates to a device for removing whipstocks from bore holes and, more particularly, to a device adapted to be included within a drill string above the bit for effecting such result.

For the purpose of producing deviations of bore holes from their original directions, whipstocks are frequently used for guiding drill bits in directions sloping with respect to the original bore hole axes. In certain cases such whipstocks are arranged to be permanently located in the bore hole by being cemented therein. In other cases, however, the whipstocks are made removable so that they may be removed and re-used, their presence in the bore hole after drilling of a deviating extension being generally unnecessary inasmuch as subsequent drilling will follow the path of the portion of the bore hole drilled by the tool which was originally deviated by the whipstock. While a removable whipstock may be recovered by a fishing operation following removal of the drill string, considerable time may be saved by removing the whipstock with the drill string. A proposal has been made to effect such removal by causing the drill bit to engage a collar on the upper end of a whipstock to pull it from the hole when the drill string is raised. The use of such a device, however, is not always satisfactory because it precludes the removal of the drill string to replace a worn or broken bit without the simultaneous removal of the whipstock.

It is the general object of the present invention to provide means whereby the whipstock may be removed from the bore hole with the drill string but need not necessarily be removed with the drill string, so that the latter, if need arises, may be removed from the bore hole to replace a bit or for other purposes while the whipstock remains in its original position to serve for the guidance of another bit.

This and subsidiary objects of the invention will become apparent from the following description read in conjunction with the accompanying drawing in which:

Figure 1 illustrates a section of a bore hole and shows in elevation a whipstock secured to a drill stem in position for location in the bore hole;

Figure 2 is a similar section, but showing the relationship of the whipstock and drill string following the drilling of a deviated hole and prior to removal of the whipstock;

Figure 3 is a vertical section through an improved device included within the drill string for effecting the removal of the whipstock; and

Figure 4 is a transverse section taken on the plane indicated at 4—4 in Figure 3.

Referring first to Figure 1, there is illustrated therein a whipstock 2 of substantially conventional character, provided with a concave sloping bit guiding surface 4 and a wedge-shaped lower end 6 arranged to be driven into the soil at the bottom of a bore hole. The whipstock is provided at its upper end with a collar 8 having an opening sufficiently large to pass a drill bit 12. This drill bit or a collar of similar outside diameter located above it on the drill stem 10 is arranged to be secured to the collar 8 by means of a shear pin 14. This pin 14 is made sufficiently strong so that before it is sheared off by the weight of the drill string the whipstock 2 will be driven sufficiently far into the earth at the bottom of the bore hole to hold it securely during the drilling operation and also prevent its removal without the application of substantial upward force to the drill string. Before it is driven into the bottom of the bore hole, the whipstock may be oriented in any conventional fashion.

It will be noted that the upper end of the drill bit is tapered to insure that it may be lifted freely through the collar 8 without exerting any such force on the collar as would tend to lift the whipstock from the position in which it is fixed. Consequently, with the arrangement described, drilling may proceed as indicated in Figure 2 and the bit may be removed and reinserted in the bore hole as often as desired without effecting removal of the whipstock.

Located at a suitable point above the bit, immediately above it if it is desired that the whipstock should be hauled out of the bore hole extending below the bit, or substantially above the bit if the whipstock is to be hauled out above the bit, is a lower section 18 of the drill stem which desirably has a diameter approximately that of the drill bit so as to pass through the collar 8 with a fairly close fit, its lower end being tapered to insure free passage. This section 18 of the drill stem is provided with longitudinal slots 20 within which are pivoted at 24 members 22 normally held within the perimeter of the section 18 by leaf springs 26 secured, as indicated at 28, to the section 18. Preferably, the springs 26 and the members 22 rather closely fit the walls of the slots 20 to prevent to a considerable extent leakage of the circulating mud at this point so that it is forced through the usual passages in the drill stem to the bit. A small amount of leakage at this point, however, is not harmful.

When it is desired to remove the whipstock

from the hole, the drill stem is lowered to such an extent that the element 18 is below the collar 8. When it is in such position, a go-devil 30 may be dropped within the drill stem to engage the wedge-shaped portions 23 of the members 22 to cam the latter outwardly and then, by engagement with the tapered walls 32 of the central passage of the element 18, to be retained in a position between the members 22 with the result that they cannot be forced inwardly by outside pressure. When expanded, the members 22 will occupy the positions shown in construction lines in Figure 3, below the collar 8, also shown in construction lines in that figure. It will be obvious that under these conditions sufficient force applied to the drill stem will dislodge the whipstock from its position and cause it to be raised with the drill stem.

In the event that the go-devil should be dropped and then decision made not to haul out the whipstock by means of the drill string, the go-devil may be removed by means of a catcher engageable with the element 34 located at its upper end. When so removed, the springs 26 will retract the members 22 within the perimeter of the element 18.

To provide free circulation of mud throughout all of the portions described above, suitable grooves may be provided to by-pass the mud both 30 on the inside and outside of the various elements. For example, the grooves 36 serve to permit mud to flow by the go-devil 30 when it is in its lower-most position, and grooves 38, running longitudinally of the outside, permit the exterior passage of mud.

It will be clear that the invention may be embodied in various forms other than that specifically disclosed. For example, other means than a go-devil may be provided for the purpose 40 of actuating devices to engage a whipstock.

What I claim and desire to protect by Letters Patent is:

1. The combination with a whipstock comprising a body arranged to penetrate the bottom of a bore hole and provided with a sloping drill guiding surface and a collar at the upper portion of the body, of a device arranged to be included in a drill string, said device being arranged to pass through said collar, and being provided with means expandible outwardly to engage said collar whereby the whipstock may be removed from a hole by means of a drill string including said device.

2. The combination with a whipstock comprising a body arranged to penetrate the bottom of a bore hole and provided with a sloping drill guiding surface and a collar at the upper portion of the body, of a device arranged to be included in a drill string, said device being arranged to pass through said collar, and being provided with means expandible outwardly to engage said collar whereby the whipstock may be removed from a hole by means of a drill string including said device, and means for normally maintaining said expandible means within the perimeter of said device to permit free passage of the device through said collar.

3. The combination with a whipstock comprising a body arranged to penetrate the bottom of a bore hole and provided with a sloping drill guiding surface and a collar at the upper portion of the body, of a device arranged to be included in a drill string, said device being arranged to pass through said collar, and being provided with means expandible outwardly to engage said collar whereby the whipstock may be removed from a hole by means of a drill string including said device, said expandible means being movable by the dropping of a go-devil to effect its expansion.

4. Means for effecting removal of a whipstock from a bore hole comprising a body arranged to be included in a drill string above the bit and means carried by said body and expandible outwardly to engage and lift a whipstock with the drill stem.

5. Means for effecting removal of a whipstock from a bore hole comprising a body arranged to be included in a drill string above the bit, means carried by said body and expandible outwardly to engage and lift a whipstock with the drill stem, and means for normally maintaining said expandible means within the perimeter of said body.

6. Means for effecting removal of a whipstock from a bore hole comprising a body arranged to be included in a drill string above the bit and means carried by said body and expandible outwardly to engage and lift a whipstock with the drill stem, said expandible means being movable by the dropping of a go-devil to effect its expansion.

7. Means for effecting removal of a whipstock from a bore hole comprising a body arranged to be included in a drill string above the bit and means carried by said body and expandible outwardly to engage and lift a whipstock with the drill stem, said means comprising at least one lever pivoted in said body and arranged to move from a position within the perimeter of said body to a position outside the same.

8. Means for effecting removal of a whipstock from a bore hole comprising a body arranged to be included in a drill string above the bit and means carried by said body and expandible outwardly to engage and lift a whipstock with the drill stem, said means comprising at least one lever pivoted in said body and arranged to be moved by a go-devil from a position within the perimeter of said body to a position outside the same.

9. Means for effecting removal of a whipstock from a bore hole comprising a body arranged to be included in a drill string above the bit and means carried by said body and expandible outwardly to engage and lift a whipstock with the drill stem, said means comprising at least one lever pivoted in said body and arranged to be moved by a go-devil from a position within the perimeter of said body to a position outside the same and to be locked by the go-devil in the latter position.
